CHAIR BACK ADJUSTING MEANS

Joseph White, Jackson Heights, N. Y.

Application March 27, 1945, Serial No. 585,108

2 Claims. (Cl. 155—160)

1

This invention relates to adjustable stop hinges and to articles associated therewith.

One object of the invention is to provide improved means for a positive stop action adjustable at a point remote from the hinge and without relying upon the uncertain action of frictional clamps or spring catches.

Another object of the invention is the provision of a hinge having adjustable stop means located along and preferably largely concealed within a coacting wall or frame member, and being desirably reenforced by the latter.

Another object of the invention is to furnish a device of the character described including cam means in improved association with adjustable stop elements whereby swinging movement is stopped in one direction but is free to occur in an opposite direction.

Another object of the invention is to construct a device of the type mentioned having improved adjustable stop hinge means including a cam and settable means for locking a bar at a given angle and preventing relative movement thereof in either direction.

More particularly, the invention may be embodied with substantial advantage in chairs having swingable backs for sitting and reclining positions. Heretofore such chairs have been provided with adjustable stops not associated with the hinges. These stops generally consisted of thumbscrews frictionally bearing on a rod to prevent longitudinal movement thereof. Such thumbscrews require a very powerful grip for tightening, and often the rod against which screw bears becomes chewed up and the stop yields and slips. If the thumbscrew is loosened, the back may accidentally drop all the way rearward. By the present invention, the adjustment is very easily made and controlled at all times, and this can be accomplished even by the invalid seated in the chair. Frequently the invalid desires to sit up straight for a short while, but with the back of the chair locked, he has no support unless he releases the adjustment. With the present invention such frequent changes of adjustment are not necessary, but when an adjustment is desired it can be made very quickly with only one turn or less of a conveniently located knob.

Generally described, the invention provides a hinge or journal including a relatively fixed cam, and a follower rod for the cam slidable in a bore or tube of one of the parts interconnected by the hinge, the range of reciprocation or other movement of the follower rod being limited by an adjustable stop which may form a cap or plug

2

having, for instance, a running thread engagement with the part in which the follower rod is sleeved. The follower rod may be as long as the part will permit, for remote control of the stop hinge, and the follower rod may act in compression, with the encasing part concealing and reinforcing it against bending strains which occur due to its thinness. As the distance between the cooperating cam surface and the cap increases, an idler is free and may be loose, but as soon as hinging movement decreases that distance, the rod is placed under compression and stops the swinging movement in one direction. However, angular movement may freely occur in the opposite direction, and especially in a reclining chair; the back may thus be freely swung to upright position by a spring or other yielding force. If it be desired to modify the device to afford a positive stop against hinging movements in both directions, then the follower rod is positively connected to the cap or stop and to the cam whereby the rod acts in compression and in tension for respective swinging movements in opposite directions. When under tension, certain deflections are caused in the rod which may render it desirable to provide a link at the point where the rod engages the cam.

Other objects and advantages of the invention will become apparent as the specification proceeds.

With the aforesaid objects in view, the invention comprises the novel features, combinations and arrangements of parts hereinafter described in their preferred embodiments, pointed out in the subjoined claims, and illustrated in the annexed drawing, wherein like parts are designated by the same reference characters throughout the several views.

In the drawing:

Fig. 1 is a fragmentary view in elevation with parts removed and other parts in section showing an adjustable reclining chair embodying the invention.

Fig. 2 is an enlarged sectional view taken on line 2—2 of Fig. 1.

Fig. 3 is a vertical sectional view through the hinge and back of the chair when said back is in vertical position.

Fig. 4 is a sectional view of a modification whereby the cam follower rod is adapted to act in compression and in tension to lock the back against swinging either forward or backward.

The advantages of the invention as here outlined are best realized when all of its features and instrumentalities are combined, but, useful

embodiments may be produced involving less than the whole.

It will be obvious to those skilled in the art to which the invention appertains, that the same may be incorporated in several different constructions. The accompanying drawing, therefore, is submitted merely as showing a preferred exemplification of the invention.

Referring in detail to the drawing, 10 denotes a reclining chair exemplifying a structure embodying the invention. The said chair may comprise a seat 11 of metal, composition or other suitable material carried by a frame including rear and front legs 12, 13, interconnected by cross ribs 14, the rear legs forming upwardly extending standards 15 connected by the arm bars 16 to the front legs 13. A swingable back 17 for the chair may include any suitable frame comprising cross bars 17a and upright marginal tubular members 18. In one or both of said members is disposed a cam follower rod 19 slideable in the tube along a path which may be lengthened or shortened by a stop or cap 20 having threaded engagement with the upper end portion of the tubular member 18.

Hinge means 21 connects the tubular member 18 with the frame or rear legs 12 at any suitable point preferably adjacent to the seat 11. A bracket 22 is bolted to the frame at 23, this bracket having a pair of arms 24. Between the latter is disposed a disc 25 in camming relation to the follower 19 as will be apparent hereinafter. Also disposed between the arms 24 and journaled on said disc is a cam ring element 26 carrying a follower head 27. Formed at the lower end of the tubular element 18 is a bracket or pair of arms 28 spaced to receive the arms 24. Interconnecting the disc element 25 with the arms 24 is a pin 29 which is free of the arms 28. A bolt 30 passes through arms 24, 28 and the disc element 25. Thus the bolt cooperates with the pin 29 to hold the disc element in fixed position, this bolt pivotally mounting the tubular element 18 for hinging movement. The arrangement of the device 21 is such that for a particular setting of the cap 20, counterclockwise movement of the element 18 is resisted because the rod 19 acts in compression between the cap and the head 27, this causing a stress on the cam ring 26 concentric with the element 25, but eccentric to the pivot bolt 30.

The camming coaction referred to is obtained because the axis of the aligned elements 19 and 27 is eccentric to the pivot 30 of the cam ring 26. Accordingly there is produced a triangle of forces of which one apex may be regarded as located at 20, another at the center of the bolt 30 and a third at the true center 31 of the disc and ring elements 25, 26. Counterclockwise motion is resisted, since the side 20, 31 of the triangle is under a compression resisted by the rod 19, and the side 20, 30 of the triangle is under a tension resisted by the tubular element 18. Preferably the location of the bolt or pivot 30 is above and forward of the axis 31 while the axis of 19, 27 is rearward of the axis 30 thus affording a maximum range of adjustment for the back of the chair. The back 17 is free to swing forward because while the triangle side 20, 30 is of fixed length, the other side determined by the length of the elements 19, 27 varies since these elements are free to separate and the element 19 is free to separate from the cap 20. This is of advantage because the back can freely swing forward to follow a person who wishes to sit

upright for a short while, and does not desire to change the stop adjustment for the back. The latter may be yieldingly urged forwardly, by a spring 32 that may in practice be encased in a tube of rubber or cloth. This spring may have a tension only sufficient to impart a light support and to yield readily when the occupant of the chair returns to reclining position. However, this spring may be omitted. In the drawing it is shown stretched for convenience of illustration.

For increased reclining, the cap 20 is merely upwardly unscrewed slightly and for a more upright position the cap is downwardly screwed somewhat. A single turn may afford a substantial adjustment. There is no chance of the back 17 accidentally falling all the way rearward, as where a frictional thumbscrew was loosened. The back drops rearwardly only as the cap is unscrewed. And where a person sits upright, the back may be instantly moved upright and locked by a spin of the cap 20.

The invention may be embodied in a door check or stop to prevent accidental closing of a door, or to limit or prevent opening of a door, and it may be embodied in a linkage for transmitting power or for movably supporting an object such as a lamp or telephone, for instance at the cap 20.

In Fig. 4 is shown a modification of the invention whereby a body such as the chair back 17 or other article can be angularly adjustably moved to a required position and there locked against movement in either direction. In this device 35, the bracket 22, disc 25 and ring 26 are the same as before, but for the tube 18 and rod 19 there are substituted tube 36 and rod 37, the latter being connected to the ring, the tube having connected at its upper end the bushings 38, 39 which are swiveled together at 40 by annularly interengaging lips. The bushing 38 is connected to the tube by a thread 41 while bushing 39 is connected to the rod 37 by a thread 42. Peripheral portions of both bushings are exposed for easy engagement and individual turning. Normally, the bushing 38 is stationary as by means of a reasonably tight thread, while bushing 39 is freely rotated to adjust the rod 37. Accordingly the rod 37 is subjected to compression when as in the chair 10, a counterclockwise force is exerted on the back 17, and to tension when a clockwise force is exerted on the back 17. Movement in either direction is thus resisted and may be obtained only by turning the bushing 39 in the proper direction. When the rod 37 is subjected to axial strain, as when under tension, the camming action may be such that a force results at a slight angle to the rod. To permit the desired deflection, the element 37 may include a link 43 pivotally connected to the main part of the rod 37 by a pin 44, this link being sufficiently narrow or tapered to have clearance with the wall of the tube. This clearance is sufficiently large to allow the necessary angular movement of the link, and the tube may laterally support the link at the limits of its movement. In the chair 10 such link is unnecessary because the head 27 is separate of the rod 19 and may have the necessary small clearance with the tube 18.

The device 35 may be readily transformed into a device such as 10 by merely freeing the rod of its fixed engagement with a relatively stationary part such as the bushing 39, and interposing an obstruction to afford an end bearing surface for the rod. Thus the thread 42 may be of sufficient length to receive a plug 45. The latter may be

screwed in and the bushing 38 unscrewed until the rod releases bushing 39 and bears on the plug 45. Now only bushing 38 is turned for adjustment, bushing 39 moving therewith.

I claim:

1. A device including a supporting member, a movable member pivotally connected thereto, one of the members being hollow, a closure means having adjustable threaded engagement with the hollow member at an end thereof remote from the pivot, a disc-like means at the pivot, said disc-like means being secured to one of the members, a cam ring journaled on the disc-like means, a follower rod slideable in the hollow member and being pivotally connected to the cam ring, the hollow member being eccentrically connected to the disc-like means, the closure means including a plurality of interconnected elements, one of the elements being swiveled on the other and being connected to the follower rod at the adjacent end of the latter, whereby the follower rod is adapted to act both in compression and in tension to prevent relative angular movement between the members.

2. A device including a supporting member, a member pivotally connected thereto, one member being a tube, a rod slideable in the tube, means at the pivot having camming coaction with the rod at one end thereof so that the rod constitutes a cam follower, the cam means including a disc fixed on the other member, and a cam ring journaled on the disc and pivotally connected to the rod and being rotatable about an axis eccentric

ally related to the pivotal connection of the tubular member so that longitudinal movement of the rod occurs relative to the tubular member upon adjustable relative angular motion between the members, and adjusting means connected to the tubular member and connected to the rod at the other end of the latter to prevent the movement of the rod with the same acting in compression and in tension to thus prevent the said relative angular movement, the adjusting means including a first element having threaded engagement with the tubular element, a second element swiveled on the first element and adapted for threaded engagement with the follower rod, and a third stop element for the rod adjustably engaged with the second element and adapted to separate the rod against threaded engagement with the second element.
